UNITED STATES PATENT OFFICE.

DUNCAN RICE, OF ABERDEEN, SCOTLAND.

TOY.

1,331,941.

Specification of Letters Patent. Patented Feb. 24, 1920.

Application filed May 31, 1919. Serial No. 300,864.

To all whom it may concern:

Be it known that I, DUNCAN RICE, a subject of the King of Great Britain, residing at Aberdeen, Scotland, have invented new and useful Improvements in Toys, of which the following is a specification.

This invention relates to toys and comprehends the provision of a device resembling the tank used in the recent war, and 10 mechanically propelled over the ground or surface by endless track belts similar to those used on the tanks above referred to.

In carrying out my invention, I provide the toy on one or both sides with a pivotally 15 mounted gun, in combination with means for moving the gun in different directions simultaneously with the progress of the toy over the ground or surface.

Another important characteristic of the 20 invention resides in the provision of means for making a noise or sound indicative of the firing of the gun, as the latter is swung upon its pivot through the instrumentality of the means above mentioned.

It is my purpose, should the toy be 25 equipped with a gun on each side thereof, to arrange the mechanism for moving the gun, and producing sounds indicative of the firing of the gun, in a manner so that these 30 operations will alternately take place from opposite sides of the toy.

The nature and advantages of the invention will be better understood when the following detailed description is taken in connection 35 with the accompanying drawings, the invention residing in the construction, combination and arrangement of parts as claimed.

In the drawings forming part of this 40 specification, like numerals of reference indicate similar parts of the several views, and wherein:

Figure 1 is a perspective view of a toy 45 designed in accordance with my invention.

Fig. 2 is a longitudinal sectional view therethrough.

Fig. 3 is an enlarged transverse sectional view taken on line 3—3 of Fig. 1.

Fig. 4 is an enlarged detail view of the 50 mechanism for moving the gun upon its pivot, and producing sound indicative of the firing of the gun.

Fig. 5 is a detail view of the driving wheel showing the ratchet teeth thereon.

Fig. 6 is a detail view of the winding 55 stem for the mechanism.

Fig. 7 is a fragmentary bottom plan view of one of the tractors.

In carrying out my invention, I make use of a casing having a configuration similar 60 to the wellknown shape or design of the tank used during the recent war, except that the top of the tank is provided with a centrally raised oblong portion 11. The tank indicated at 10 may be constructed from any 65 suitable material and may also vary in size without departing from the spirit of the invention, the tank being propelled by means of the endless tractors 12 in a manner to be hereinafter more fully described. Secured 70 in any suitable manner to each of the side walls 13 of the tank, is a wall 14, and these walls 14 are spaced an appreciable distance from the adjacent walls of the tank to define a chamber for the reception of certain parts 75 of the operating mechanism, this space being closed however by the tractors 12 as shown. The tractors are made up of a plurality of blocks of any suitable material, the blocks being hinged or otherwise suitably 80 joined together to afford the tractor the desired flexibility.

Arranged at each side of the tank 10 and positioned in the space therebetween and the adjacent walls 14, is a relatively large 85 cog wheel 15 and series of relatively spaced cog wheels 16, the respective series of the latter mentioned wheels being disposed in advance of and at the rear of the large wheel 15 and adjacent the lower run of the tractor 90 with which it engages. Each of the blocks constituting the tractors 12 is provided with a centrally located opening 17 for the reception of the teeth of all of the cog wheels above mentioned, thus driving the tractors. 95 A transversely disposed shaft 18 connects the relatively larger cog wheel 15 at the opposite sides of the tank, while fixed upon the shaft adjacent one end thereof is a relatively small cog wheel 19 which is also positioned in the space between the adjacent wall 14 and the corresponding side wall of the tank. A vertically disposed shaft 20 has fixed thereon a drive wheel 21 which is horizontally disposed and provided with 100 teeth 22 on its underside to mesh with the cog wheel 19 for the purpose of rotating the transversely disposed shaft 18.

The motive power for the toy is derived from the spring 23 mounted upon the upper side of the drive wheel 21, and as the latter wheel is driven, it rotates the cog wheel 19 and the shaft 18 with which the cog wheel is connected, and also the relatively large gears 15 at opposite sides of the tank which are connected by means of the shaft 18.

The raised portion 11 of the tank is provided with an opening for the reception of a hollow winding stem 24 which fits over the upper part of the vertically disposed shaft 20, the stem carrying at its lower end a cam 25 which is positioned between the spring 23 and the drive wheel 21. The cam 25 fits within a circle defined by a plurality of ratchet teeth 26 rising from the drive wheel 21, a construction which permits the stem to be turned in one direction to wind the spring 23 and turn in an opposite direction without having any effect upon the spring whatever.

Carried by each side of the tank is a gun 27 mounted for pivotal movement. With a view of moving the guns into different positions as the tank travels over the ground or surface, I provide each of the large cog wheels 15 with a disk 28 from which projects a plurality of lugs or fingers 29. Projecting from the adjacent end of the gun at each side of the tank, is an arm 30 terminating in the path of movement of the lugs or fingers 29, and consequently as the cog wheels 15 rotate turning the disk 28, the lugs or fingers are brought into engagement with the arm 30 with a result that the guns are turned upon their pivots, in different directions. It is to be understood, that the lugs or fingers 29 at one side of the tank are disposed with regard to the fingers at the opposite sides of the tank so that the guns are alternately moved at either side of the tank. A spring 20' is terminally secured to each gun and a fixed part of the casing, said spring yieldably holding the gun in a straight normal position.

It is also my purpose to provide a means for producing a sound indicative of the firing of the gun, and as shown in this specific instance this means consists in the use of a leaf spring 31 secured to the wall 14 at both sides of the machine, the free end of each spring being disposed to ride over the teeth 32 formed on the periphery of the adjacent disk 28. These teeth 30 extend only a part of the way around the circumference of the disk the remaining portion of the circumference being smooth as indicated at 33. As the guns at the opposite sides of the machine move alternately, it is desired to have the sound indicative of the firing of the gun to take place at each side of the machine alternately, and simultaneously with the movement of the adjacent gun. Therefore, the teeth 32 are disposed at a different part

in the circumference of the respective disk, so that when the spring 31 is coöperating with the teeth 32, of the disk at one side of the machine to produce the sound above mentioned, the spring 31 at the opposite side of the machine is moving over the smooth portion 33 of its coöperating disk 28.

While I have shown and described what I consider the preferred embodiment of the invention, I desire to have it understood that what is herein shown and described is merely illustrative, to which I do not limit myself, and that such changes may be resorted to when desired as fall within the scope of what is claimed.

What I claim is:—

1. In a toy of the character described, a tank, means for propelling said tank, a gun mounted on each side of the tank for pivotal movement, means for controlling the movement of the guns and alternately operating the latter, and means for producing sound at either side of the machine simultaneously with the movement of either gun to resemble the sounding or firing of the guns.

2. In a toy of the character described, a tank, means for propelling said tank, guns pivotally mounted at the opposite sides of the tank, means for independently moving said guns upon their pivots and means operable from either side of the machine to produce sound indicative of the firing of the gun, said last mentioned means being actuated from that side of the tank upon which the gun is being moved.

3. In a toy of the character described, comprising a portable casing, means for propelling the same including a rotatable shaft, a spring pressed gun mounted at each side of the casing for pivotal movement, an arm projecting from one end of the gun, a disk on the adjacent end of the shaft, fingers projecting from said disk and successively engaging said arm to turn the gun upon its pivot, and means operating simultaneously with the movement of the gun for producing a sound indicative of the firing of the gun.

4. In a toy of the character described, comprising a portable casing, means for propelling the same including a rotatable shaft, a spring pressed gun mounted at each side of the casing for pivotal movement, an arm projecting from one end of the gun, a disk on the adjacent end of the shaft, a connection between the disk and said arm for intermittently moving the gun upon its pivot, said disk having teeth around a portion of the periphery thereof, a resilient element coöperating with said teeth to produce a sound indicative of the firing of the gun, simultaneously upon movement of the latter.

5. In a toy of the class described compris-

ing a tank, having spaced walls at the sides thereof, endless tractors movable over the edges of the said spaced walls inclosing the space between the walls, means for operating said tractors, guns pivotally mounted on the opposite sides of the tank, a transversely disposed shaft journaled in the opposite sides of the tank, means for rotating

said shaft, and a connection between the opposite ends of the shaft and the adjacent 10 guns for alternately swinging the guns upon their pivot in different directions horizontally.

In testimony whereof I affix my signature.

DUNCAN RICE.
